UNITED STATES PATENT OFFICE.

GILBERT J. CLARK, OF MAYVILLE, WISCONSIN.

DENTAL PLIERS.

No. 874,489.

Specification of Letters Patent.

Patented Dec. 24, 1907.

Application filed December 24, 1906. Serial No. 349,299.

To all whom it may concern:

Be it known that I, GILBERT J. CLARK, a citizen of the United States, residing at Mayville, county of Dodge, and State of 5 Wisconsin, have invented new and useful Improvements in Dental Pliers, of which the following is a specification.

My invention relates to improvements in that class of dental pliers which are adapted 10 to be used in forming the vertical metallic walls of dental crowns, and it pertains more especially, 1st to the peculiar construction and configuration of the two opposing bearing surfaces of the jaws of the pliers which 15 are adapted to grasp the interior and exterior surfaces of the cap or shell from which the crown is formed, whereby a single firm grip of the pliers the walls of the shell are compressed into the desired shape conforming 20 to that of the ideally perfect tooth, whereby a much more perfect shape is given to the crown in a moment's time than it would be possible to otherwise produce in a great length of time by the most skilled workman 25 when using pliers of the ordinary construction.

In carrying out my system of forming crowns I preferably use a special pair of pliers for forming the front or labial surface 30 of the crown which conforms to the desired front surface of the tooth and another pair for the rear or lingual side of the tooth which conforms to the desired shape of such surface, and I also preferably use a similar pair 35 of pliers for each tooth whereby it is obvious that a crown may be readily made to conform in all respects to the shape of the ideally perfect tooth which it is intended to replace in the shortest possible time.

40 My invention pertains second to the construction of the back and end of one of the jaws of the pliers whereby the top and both sides of a crown may, as it is being formed, from a metallic band, be given the desired 45 shape of a perfect tooth before such band is removed from the pliers.

The construction of my invention is explained by reference to the accompanying drawings in which,

50 Figure 1 is a side view of one of the several pairs of pliers used in my set for the purposes mentioned. Fig. 2 is a front end view of a pair of pliers in an open position. Figs. 3 and 4 represent the opposing sides of the 55 gripping surfaces of a pair of jaws, shown in Fig. 2, separate from each other. Fig. 5

represents a hollow metallic shell as it is formed preparatory to being acted upon by my pliers in the process of forming a crown. Fig. 6 represents the position of the shell as 60 it is grasped by the jaws of the pliers preparatory to being compressed to the desired shape one side of said shell being represented as it appears after it has been acted upon by the pliers. Fig. 7 represents the vertical 65 walls of the crown as they appear after they have been acted upon by the pliers. Fig. 8 is a modified form of pliers in which the back of one of the jaws is shaped to conform to the desired shape of one side of a tooth, while the 70 opposing surfaces of the jaws are shaped to conform to the opposite side of the tooth said pliers being adapted to be used when constructing a cap from a metallic band before the ends of the bands are soldered together. 75 Fig. 9 represents a band from which a crown is formed between the jaws of a pair of pliers, shown in Fig. 8. It will be understood that when the band is gripped between the jaws of the pliers, as indicated in Fig. 9, one side 80 of the band is given the desired shape by the action of the jaws which are brought together against it, while the opposite side of the band is given the desired shape by pressing or burnishing it against the back of the 85 jaw when in the grip of the pliers. When the band has been thus given the desired shape it is removed from the pliers and its opposing ends are soldered or brazed in the usual way. Figs. 10 and 11 are the opposing 90 sides of the jaws of the pliers shown in Fig. 8.

Like parts are identified by the same reference figures throughout the several views.

1 and 2 represent the respective handles of the pliers and 3 and 4 the respective jaws 95 of the pliers which are used in giving a hollow shell or cap 5 the desired shape to correspond with the vertical sides of an ideally perfect crown.

In using the pliers shown in Fig. 1 the jaw 100 3 is placed within the shell or against its inner concave surface and the jaw 4 against its exterior surface as indicated in Fig. 6 when the jaws are brought firmly together against the shell by the pressure of the operator upon the handles, whereby the desired shape will be given to one side of the crown as indicated in Fig. 6, when the shell is removed from such pair of pliers and placed between the jaws of another pair of pliers, the gripping surface of 110 which conform to the desired shape of the opposite side of the crown when the pliers

are brought together in like manner against the opposite side of the crown, whereby both sides of the shell are given the desired shape as indicated in Fig. 7, while the jaws of the 5 pliers shown in Fig. 1 conform to the shape of the smaller teeth, the jaws shown in Figs. 2, 3, 4 and 6, conform to the shape of the larger side teeth, it being understood that similar jaws to such two forms indicated are 10 provided for several forms of teeth of both the upper and lower sets, whereby it is obvious that when the shell has been formed as shown in Fig. 5, it can be readily and quickly transformed into the desired shape to properly represent the tooth it is intended to replace.

The pliers thus far described in Figs. 1 to 8 inclusive are adapted to be used as stated for forming the vertical side walls only of a 15 crown, it being understood that when such parts of a crown have been formed the top or biting surface of a crown, which has been previously formed by the ordinary process, is secured to such side walls by brazing or 20 soldering in the ordinary manner. The jaws of the pliers shown in Figs. 9 and 11 inclusive are adapted not only to form the wall of one side of a crown as they are brought together against the same but also serve to hold the 25 band from which the crown is formed in place while the opposite sides thereof are brought together and burnished or compressed against the back of one of the jaws and thereby given the required shape con- 30 forming to the desired shape of the end and opposite side of the tooth. When the band has been thus acted upon, it is removed from the pliers and the opposing ends of the band from which it is formed are soldered together, 35 thus forming a complete crown including the vertical walls and biting surface. One of the jaws 3 shown in Fig. 1 is provided with a convex surface 6 while the opposite jaw 4 is provided with a concave surface 7 which con- 40 forms in shape to and is adapted to closely fit against the convex surface of the jaw 3. The jaw 3 shown in Fig. 3 is provided with convex surfaces 8, 8, and concave surface 9, while the jaw 4, shown in Fig. 4, is provided 45 with concave surfaces 10, 10 which are adapted to conform in shape to the surfaces 8, 8 of Fig. 3 and said jaw 4 is also provided with a convex surface 11 which is adapted to conform in shape to the concave surface 9 shown 50 in Fig. 3, whereby as said jaws are brought together against the metallic shell, such shell will be pressed by the convex surface of one of the jaws into the concave surface of the other and thereby given the desired shape.

55 In Figs. 8 and 9 the back of the jaw 12 is shaped to conform to the shape of one side of a tooth, as shown at 13 in said figures, while the opposite side 14 of said jaw is shaped to conform to the opposite side of a tooth

whereby when the jaws are brought together 65 against the band 15 that portion of the band between the jaws 12 and 16 will as stated be compressed into the desired shape to form the labial side of a tooth. This being done the ends of the band 15 are pressed by a suitable burnishing tool against the back of the jaw until they conform to the shape thereof when the band thus formed is removed and its contiguous ends brazed together as previously described. 70

75 While I have shown and described instruments for producing three different forms of crowns, it will of course be understood that by a complete set of instruments such as described all the necessary crowns for a complete set of teeth may be formed in like manner. 80

85 For brevity of description the opposing surfaces of the jaws are referred to in the claims as male and female dies.

Having thus described my invention what I claim as new and desire to secure by Letters Patent is,

90 1. A pair of dental pliers comprising a set of operating handles and jaws pivotally connected together, a male die conforming in shape to the vertical walls of a dental crown and inversely conforming to the shape of the vertical walls of a tooth, said die being formed integrally with or rigidly affixed to 95 one of said jaws, a female die conforming in shape to and adapted to register with the male die and also formed integrally with or rigidly affixed to the opposing jaw of said pliers. 100

2. A pair of dental pliers comprising a set of operating handles and jaws pivotally connected together, a male die conforming in shape to the vertical walls of a dental crown and inversely conforming to the shape of the 105 vertical walls of a tooth, said die being formed integrally with or rigidly affixed to one of said jaws, a female die conforming in shape to and adapted to register with the male die and also formed integrally with or 110 rigidly affixed to the opposing jaw of said pliers, the back of one of said jaws being shaped to conform to one side of the vertical walls of a dental crown, whereby one side of a metallic band held by said pliers may be 115 given the desired shape by the action of the two opposing jaws and said band simultaneously held by said jaws, while the opposite side of the metallic band is pressed and burnished to conform to the back of the crown-shaped jaw, all substantially as and for the purpose specified. 120

In testimony whereof I affix my signature in the presence of two witnesses.

GILBERT J. CLARK.
